UNITED STATES PATENT OFFICE.

JOHN C. SHERRY, OF SEATTLE, WASHINGTON, ASSIGNOR TO SHERRY WATER TUBE
BOILER CO., OF SEATTLE, WASHINGTON, A CORPORATION OF WASHINGTON.

BOILER HAND-HOLE PLATE.

1,304,391.

Specification of Letters Patent. Patented May 20, 1919.

Application filed May 1, 1918. Serial No. 231,789.

To all whom it may concern:

Be it known that I, JOHN C. SHERRY, a citizen of the United States, residing at Seattle, in the county of King and State of Washington, have invented new and useful Improvements in Boiler Hand-Hole Plates, of which the following is a specification.

This invention relates to hand-hole plates or closures to be used in connection with 10 boilers, tanks, and the like.

One of the objects of the present invention is to provide a hand-hole plate, particularly adapted as a closure for circular hand-holes, which is simple and substantial in 15 construction, easy to insert, and which will seat on the entire inner edge of the opening or on the side where the pressure is applied. Another object of the invention is to provide a two-piece hand-hole plate which is 20 easy to insert and readily assembled when inserted. Further objects will hereinafter appear.

The invention consists of the parts and the construction and combination of parts 25 as hereinafter more fully described and claimed, having reference to the accompanying drawings, in which—

Figure 1 is a section of a boiler plate, showing the application of the closure plate.

Fig. 2 is a plan view of same.

Fig. 3 is a side elevation of the outer section of the plate.

Fig. 4 is a plan view of same.

Fig. 5 is a perspective view of the inner 35 section of the plate.

Fig. 6 is a view, similar to Fig. 2, taken from the inside of the boiler.

Referring to the drawings in detail, A indicates a boiler plate, in which is formed 40 a circular opening 2, which, in the present instance, is closed by a hand-hole plate generally indicated at B. This plate forms the subject-matter of the present invention and consists of an inner and an outer head member, such as shown in Figs. 3, 4 and 5. The 45 inner member comprises a circular disk 3 having a diameter slightly less than the diameter of the hole 2.

Formed on the inner face of the disk 3 is 50 a pair of segmental lugs 4. Also formed in the plate is a central opening 5, through which passes a bolt 6 secured in the inner head member shown in Fig. 5. This head member also consists of a circular disk 7, 55 the sides of which are cut away, as at 8. The

cut-away portions are true circles and conform to the inner faces 9 of the lugs 4, while the outer faces 10 of the lugs 4 conform to the outer circle or diameter 11 of the disk 7. The two head members may, 60 therefore, be assembled and will, when so assembled, form a plug or plate consisting of an outer disk 3, having a diameter slightly less than the hole to be plugged, and an inner disk of larger diameter than 65 the hole to be plugged, said last named disk being formed by the plate 7 and the segmental lugs 4.

The bolt 6 is secured in the disk 7 and it is, therefore, comparatively easy to insert 70 the same as the disk 7 can be turned into alignment with the lugs 4, thus presenting a diameter slightly less than the hole 2. The two plates are thus easily inserted and a quarter turn of the inner disk 7 immediately 75 brings it into register with the lugs 4, thus permitting it to seat between same and assume the position shown in Figs. 1 and 6.

A packing gasket 12 may then be inserted between the inner head and the plate A and thus forms a seal between the hand-hole plate and the opening through which neither steam nor water can leak. Any 80 form of spider may be used for the reception of the bolt 6 and the nut 14, but preferably a three legged spider, such as shown at 15, is used. This may be slotted on one side, as at 16, to permit it to be slipped under the nut 14 of the bolt, or it may be 85 provided with a single central opening, if desired. The hand-hole plate is adapted both for small and large openings and may, therefore, be termed not only a hand-hole plate but may also be termed a plug or 90 stopper.

The materials and finish of the gasket 12 and the sections forming the hand-hole plate may be such as the experience and judgment of the manufacturer may dictate. 100

I wish it understood that various changes in form, proportions and minor details of construction may be resorted to within the scope of the appended claims and that I do not wish to limit myself to the specific 105 design and construction here shown.

Having thus described my invention, what I claim and desire to secure by Letters Patent is—

1. A hand-hole plate for boilers and the 110

- like, comprising an inner and an outer head member, said inner head member comprising a circular disk having a diameter slightly less than the opening to be closed, 5 a pair of segmental lugs forming a portion of said disk, each of said lugs having an outer face forming a portion of a circle of larger diameter than the hole to be closed, an inner head section adapted to be received 10 by the outer head section consisting of a disk having a diameter larger than the opening to be closed and conforming to the circle forming the outer faces of the lugs formed on the outer head, a pair of cut-away portions formed on each side of the inner head, the faces of said cut-away portions forming sections of circles and also conforming to the inner faces of the lugs formed on the outer head, and a bolt carried by the inner head 15 adapted to draw the head sections in unison against the inner face of the plate in which the hand-hole is formed.
2. A hand-hole closure including a bolt and a pair of sections turnable thereon, one 20 section having a pair of similar opposite concave portions and the other section having a pair of similar opposite convex portions receivable in said respective concave portions.
3. In a hand-hole closure, a bolt, a one-piece disk thereon to itself fit in the hole, said disk having opposite parts provided with interior convex faces extending within the disk periphery and exterior convex 25 faces extending beyond the disk periphery, and a plate on the bolt having concave parts to receive the interior convex faces of said disk parts and having convex parts to register with the exterior convex faces of 30 the disk parts so that said exterior convex faces of the disk parts and the convex parts of the plate will conjointly form a closure for the hole.
4. A hand-hole closure including securing 35 means and members each turnably mounted on said means, said members being formed so as to be insertible through the hole while on the securing means in one position, and upon relative turning of approximately 90° to conjointly form a closure extending beyond the margin of the hole.
5. A hand-hole closure including members each having a pair of similar and op-

positely disposed complementary depressions and projections, and securing means 55 turnably carrying each member whereby said members may be turned while on said securing means through approximately 90° so as to be insertible through the hole in one position and, in a second position to 60 conjointly form a closure extending beyond the margin of the hole.

6. A hand-hole closure including securing means and closing means movably mounted on the securing means, said closing means 65 being formed so as to be insertible through the hole in one position and while on the securing means and upon relative turning of approximately 90° to extend beyond the margin of the hole.

7. A hand-hole closure including a bolt and members turnable thereon and being of less width than length so as to allow the members to be turned and to pass through the hole in the direction of their length 75 and then turned through approximately 90° to extend at substantially right angles to each other so as to have their ends extend beyond the margin of the hole.

8. A hand-hole closure composed of a 80 bolt and a pair of superimposed members each turnably mounted on the bolt and being formed so as to pass through the hole in one position thereof and upon relative turning of approximately 90° to form a 85 complete closure for the hole.

9. A hand-hole closure composed of a bolt and superimposed members movably mounted on the bolt and each having less width than length and formed so that upon 90 relative turning of approximately 90° to provide a complete closure for the hole.

10. In a hand-hole closure, securing means, and sectional closing means carried by the securing means and formed so as to 95 be insertible through the hole and then moved through approximately 90° to close the latter.

In testimony whereof I have hereunto set my hand in the presence of two subscribers. 100

JOHN C. SHERRY.
